COMBINED LAMP AND RADIO

Anthony J. Meccariello, 42 E. Battlewood Ave.,
Oaklyn, N.J.

Filed Apr. 2, 1963, Ser. No. 74,269

Term of patent 3½ years

(Cl. D48—20)

FIG. 1

FIG. 3

FIG. 1 is a perspective view showing the front and one side of a combined lamp and radio showing my new design;

FIG. 2 is a rear elevation thereof with the shade and bulb omitted for ease of illustration, and

FIG. 3 is a reduced elevation thereof as seen from the opposite side, with the shade and bulb omitted for ease of illustration.

The dominant features of my design reside in the portions shown in full lines.

I claim:

The ornamental design for a combined lamp and radio, as shown and described.
